UNITED STATES PATENT OFFICE

HILLER D. DORFMAN, OF MANSFIELD, OHIO, ASSIGNOR TO WESTINGHOUSE ELECTRIC & MANUFACTURING COMPANY, A CORPORATION OF PENNSYLVANIA

THERMOSTATIC DEVICE

Application filed November 10, 1937. Serial No. 232,291.

The invention relates to thermostatic devices and particularly to thermostatic switches.

An object of the invention is to provide a thermostatic switch that shall be simple and efficient in its operation and easily manufactured and installed.

And a further object of the invention is to provide a thermostatic switch for electric energy translating devices that shall be operable to protect the device from moderate overloads long continued and from abnormal or severe overloads of short duration.

In practicing my invention, I provide a thermostatic switch, for protecting electric motors and similar devices from overloads, with a heater for heating the thermal element of the switch by conduction and a heater for heating the thermal element by radiant heat, both heaters being energized by current traversing the motor. The conduction heater effects actuation of the switch, and consequent deenergization of the motor, responsive to moderate overloads long continued, and the radiant heater becomes effective and responsive to abnormal overloads of short duration to actuate the switch.

For a fuller understanding of the invention reference may be had to the following description taken in conjunction with the accompanying drawings, in which:

Figure 1 is a bottom plan view of a thermostatic switch base for the device embodying the invention;

Fig. 2 is a top plan view of the same base;

Fig. 3 is a view partially in side elevation and partially in section, of a thermostatic switch embodying the invention; and

Figs. 4 and 5 are schematic illustrations of circuits and apparatus embodying the invention.

In the drawings, a base 1 is illustrated on a bottom face of which are disposed concentric washers 2 and 3, of suitable insulating material, having different diameters. The washers are provided with openings at the center thereof which are in alignment with an opening at substantially the central portion of the base 1. The washers may be secured to the base by an internally screw-threaded eye-

let or bushing 4, one edge of which may be peened over against the base and the other of which may be peened over against the surface of washer 3 in order to hold the washers securely thereagainst.

A plurality of contact members 5 to 9, inclusive, of arcuate shape are disposed along the circumference of the washer 3 and rest upon the face of the washer 2.

The upper face of the base 1 is provided with a heating element 10 that is disposed between sheets 11 and 12 of electric-insulating material. In order that the contact members 5 to 9, inclusive, the heating element 10, and the sheets 11 and 12 may be secured firmly to the base 1, a rivet 13 and terminal members 14 to 17, inclusive, are provided.

As shown in Figs. 1 and 2, the rivet 13 extends through the sheets 11 and 12, the base 1 and the contact member 5, the lower end of the rivet being peened over against the contact member 5 in order to hold it rigidly in place.

The terminal members 14 to 17, inclusive, are provided with rivet portions that extend through the sheets 11 and 12, the base and the contact members 6 to 9, inclusive, the lower ends of the terminals being peened over against the faces of the contact members thereby holding them securely in place. The ends of the resistor element 10 may be secured to the terminals 14 and 15, in order to make electrical contact therewith.

As shown in Fig. 1 of the drawings, a heating element or resistor 18 of the radiant heat type is secured against the outer surface of the washer 3 by a lug 19. The ends of the resistor may be secured to the ends of the terminals 14 and 15, respectively, either by welding or other suitable methods.

In order that an electric circuit may be controlled between the terminals 16 and 17, a bimetallic disc 21 having contact buttons 22 to 24, inclusive, secured thereto is provided. The contact buttons may be insulated from the disc by insulating washers 25, only one of which is shown (see Fig. 3). The contact buttons are so positioned that adjacent ends of the contact members 5 to 9, inclusive, may be bridged thereby.

The disc 21 may be secured to the base by means of a stud bolt 26 that has screw-thread engagement with the bushing 4. The initial pressure existing between the contact buttons 5 22 to 24, inclusive, and the contact members 5 to 9, inclusive, may be adjusted by the stud bolt 26 by so turning it that the disc 21 is brought either closer to or moved farther away from the base 1.

10 The disc 21 may be of the type disclosed in the patent to J. A. Spencer, No. 1,448,240. This disc has the characteristic that when normally cool, or when the temperature is below a predetermined value, the shape there- 15 of may be substantially that shown in Fig. 3 of the drawings, but when heated to a higher temperature of a predetermined value, the disc will assume a reverse curve position with a snap motion thereby effecting disengagement of the contact buttons 22 and 24, inclusive, from their cooperating contact members 5 to 9, inclusive.

16 It is evident from Figs. 1, 2 and 4 of the drawings that the resistor elements 10 and 18 are connected in parallel circuit with each 20 other, but in series between the terminals 16 and 17 of the switch. Therefore, any current which flows between the terminals 16 and 17 will flow through the resistor elements 10 25 and 18.

26 The resistor elements may be so proportioned that, if a predetermined value of current say, for example, 10 amperes, flows through the resistance elements for a period 30 of twenty minutes, the resistance-element 10 will have generated sufficient heat to cause the bimetallic disc 21 to have been heated to its operating temperature by conducted heat from the base 1. The resistance element 18 35 may be so proportioned that, if ten amperes flows therethrough, sufficient heat will not have been generated thereby to affect the operation of the disc 21. However, this element may be so proportioned that, if a current of say, for example, thirty amperes flows 40 therethrough for a period of two minutes or less, the element will have generated sufficient radiant thermal energy to heat the disc 21 to its operating temperature.

45 An application of the thermostatic switch illustrated in the drawings in which the heating elements 10 and 18 are connected in parallel circuit relation with each other to an electric motor 28 is illustrated in Fig. 4 50 of the drawings. In this application, with a given design of resistor elements 10 and 18, the element 10 will be responsive to moderate current overloads to cause the motor 28 to be deenergized when the moderate overload 55 has persisted for a relatively long period of time. If, however, the motor 28 has been subjected to a severe overload so that a current of substantially short circuit value flows therethrough, the resistor 18 will respond al- 60 most instantly to generate sufficient radiant

thermal energy to effect operation of the thermostatic switch and a consequent de-energization of the motor.

65 When the resistor elements 10 and 18 are connected in parallel as shown in Fig. 4, the 70 switch may be utilized for protecting a motor having a full-load current rating of say 30 amperes, but if the switch were to be utilized with a motor having a full-load current rating of 15 amperes the resistance elements 75 would not generate sufficient thermal energy to actuate the switch to its open circuit position in time to protect the motor from over-heating. In order that the switch may be applicable to the motor of the smaller rating 80 without changing the resistance of the elements 10 and 18, the resistance elements may be connected in series as shown in Fig. 5 of the drawings. Stated in another way, if the elements 10 and 18 are connected in parallel, 85 the switch may be applied to a motor of a given horse power and designed for use on a 110-volt circuit, but if a motor of the same horse power but designed to operate on 220 90 volts, the resistance elements may be connected in series.

95 In Fig. 5 of the drawings, one terminal of the resistance element 10 is connected to one terminal of the motor and the other terminal thereof is connected to a terminal 17 of the 100 switch. Since the resistor element 18 remains connected to the terminals 14 and 15, it is evident that the resistor elements 10 and 18 are connected in series circuit relation to each other and the motor 28.

105 It is to be noted that the moment the switch has been actuated to its circuit opening position, the resistor elements 10 and 18 are deenergized whether they be connected in series or parallel, thereby permitting the disc 21 to cool and to cause it to return to its circuit closing position automatically. However, if the motor 28 is still subjected to a severe overload, the switch will be actuated to its open circuit position promptly, in order 110 to insure protection of the motor from excessive temperatures which may result from excessive current flowing therethrough.

115 Various modifications may be made in the device embodying the invention without departing from the spirit and scope thereof. It is desired, therefore, that only such limitations shall be placed thereon as are imposed by the prior art and the appended claims.

120 I claim as my invention:

1. In a thermal relay for an electric motor, in combination, a thermostatic switch for the motor, means responsive to a relatively small value of current long continued for heating the switch to its operating temperature 125 by conducted heat, and a second means responsive to a relatively large value of current of short duration for heating the switch to its operating temperature by radiant heat.

2. In a thermal relay, in combination, a 130

- base, a plurality of contact members secured thereto, a bimetallic disc supported by said base, contact members carried thereby for cooperating with said plurality of contact members, a heating unit on said base for causing the disc to be actuated responsive to heat conducted thereto from the base, and a heating element supported by said base and disposed between the disc and base for causing actuation of the disc responsive to radiant heat. 10
versed by current traversing the translating device.
- In testimony whereof, I have hereunto subscribed my name this 2d day of November, 1927. 70
HILLER D. DORFMAN. 70
3. In a thermal relay, in combination, a base, a plurality of contact members secured thereto, a bimetallic disc supported by said base, contact members carried thereby for cooperating with said plurality of contact members, means on said base for heating said base to cause actuation of the disc responsive to heat conducted thereto from the base, and means supported by said base for heating said disc by radiant heat to cause actuation thereof. 15
80
4. In a thermostatic circuit-controlling device for protecting electric motors both from moderate overloads long continued and abnormal overloads of short duration, in combination, a thermostatic switch for controlling the motor, means responsive to moderate overloads for causing the switch to be actuated, and a second means responsive to abnormal overloads for causing the switch to be actuated. 20
85
5. In a thermostatic circuit controlling device for protecting electric motors both from moderate overloads long continued and abnormal overloads of short duration, in combination, a thermostatic switch for controlling the motor, a heating element responsive to moderate overload motor current for causing the switch to be actuated by conducted heat, and a heating element responsive to abnormal overload motor current for causing the switch to be actuated by radiant heat. 25
90
6. A base for a thermostatic switch comprising a supporting plate, a plurality of spaced contact members disposed on said plate and insulated therefrom, a conduction heating unit disposed on one side of the plate, and a radiant heating unit disposed on the other side thereof. 30
95
7. In a thermostatic circuit controlling device for electric energy translating devices, in combination, a base, stationary contacts supported thereby, a thermostatic element, contacts carried thereby for cooperating with the stationary contacts to effect energization and deenergization of the translating device responsive to predetermined thermal conditions of the thermostatic element, a heating element disposed on the base for heating the thermostatic element therefrom by conduction, and a heating element disposed between the thermostatic element, and the base for heating the thermostatic element by radiant heat, said heating elements being tra- 35
